UNITED STATES PATENT OFFICE.

DAVID J. HANNA, OF PHILADELPHIA, PENNSYLVANIA.

DESIGN FOR A LOAF OF BISCUIT OR ROLLS.

47,253.

Specification for Design.

Patented Apr. 20, 1915.

Application filed December 2, 1914. Serial No. 875,168. Term of patent 7 years.

To all whom it may concern:

Be it known that I, DAVID J. HANNA, a citizen of the United States, residing in Philadelphia, Pennsylvania, have invented a new, original, and ornamental Design for a Loaf of Biscuit or Rolls, of which the following is a specification, reference being had to the accompanying drawings, in which:

Figure 1, is a perspective view of the loaf of biscuit or rolls forming the subject of my design; Fig. 2, is a plan view of the same, and Fig. 3, is an inverted plan view of the same.

My design for a loaf of biscuit or rolls is substantially circular in outline, comprising an outer row of biscuits 1 divided by radial

lines 2, with a central body comprising a series of biscuit 1^a, this central body having a substantially octagonal contour in outline; the line 3 dividing it from the outer row of biscuits. Said central body is also divided by radial lines 4 at right angles to each other; such lines terminating adjacent to the outer row of biscuits.

I claim:

The ornamental design for a loaf of biscuit or rolls, substantially as shown and described.

DAVID J. HANNA.
